CLAIM

The ornamental design for a display screen with an animated graphical user interface, as shown and described.

DESCRIPTION

The patent file contains at least one drawing executed in color. Copies of this patent with a color drawing will be provided by the Office upon request and payment of the necessary fee. FIG. 1 is a first image in a sequence of a first embodiment of display screen with an animated graphical user interface showing our new design; and FIG. 2 is a second image thereof; and FIG. 3 is a third image thereof.

FIG. 3 is a third image thereof.
FIG. 4 is a first image in a sequence of a second embodiment, a display screen with an animated graphical user interface showing our new design;

FIG. 5 is a second image thereof; and, FIG. 6 is a third image thereof.

The subject matter in this patent or application includes a process or period in which an image changes into another image. This process or period forms no part of the claimed design. The broken line showing of text elements, individual icons and the display form no part of the claimed design.
